(57) CLAIM

The ornamental design for a stand for hair drier, as shown and described.

DESCRIPTION

FIG. 1 is a front perspective view of the stand for hair drier showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof; and,

FIG. 8 is a reference view showing the state of use that a hair drier and peripheral devices have been placed on the claimed design.

The portions of FIG. 8 drawn in broken lines show environmental structure only and form no part of the claimed design.

1 Claim, 8 Drawing Sheets
